WILLIAM A. PRINGLE AND LOUIS FRED HAGEMANN, OF NIAGARA FALLS, NEW YORK,
ASSIGNORS TO AMERICAN SALES BOOK COMPANY, LIMITED, OF TORONTO, CANADA,
A CORPORATION OF ONTARIO, CANADA

MANIFOLDING DEVICE

Application filed December 13, 1927. Serial No. 239,648.

This invention relates to improvements in manifolding devices and with reference to some of its more specific features, it relates to improvements in machines for simultaneously making a plurality of copies of an inscription by means of the use of transfer or carbon sheets, and commonly known as autographic registers.

It is a general object of the invention to provide, in a machine of the class mentioned, an improved arrangement which is simple in construction and use whereby an inscription may be transferred to parts only of an auxiliary sheet or card while other parts thereof are protected from inscription reception.

Another object of the invention is to provide for machines of the class mentioned, an improved arrangement for inserting an auxiliary record card or sheet into manifolding relation with the other record sheets without disturbance to the latter.

A further object of the invention is to provide in a machine of the class mentioned, an improved support for supporting the supply of transfer or carbon strips in the usual position for machines of this class, but arranged so as to permit free insertion or removal of an auxiliary record card or sheet to or from manifolding position over the platen of the machine.

A further object is to provide in machines of the class mentioned an improved relative arrangement of an entrance slot for auxiliary record cards and a transfer sheet support or housing in such a manner as to permit free insertion or removal of the auxiliary card and to facilitate the loading of the transfer sheet into manifolding position.

Other objects will be in part obvious in connection with the following detailed description of an illustrative but preferred embodiment of the invention and will be in part pointed out therein.

The invention accordingly comprises the features of construction, combinations of elements, and arrangement of parts, which will be exemplified in the construction hereinafter set forth and the scope of the application of which will be indicated in the claims.

For a more complete understanding of the nature and objects of the invention, reference is made to the following detailed disclosure, and to the accompanying drawings, in which:

Fig. 1 is a plan view of an autographic register embodying the features of the invention.

Fig. 2 is a side elevation thereof.

Fig. 3 is an enlarged fragmentary section taken approximately on the line 3—3 of Fig. 1, looking in the direction of the arrows.

Fig. 4 is an enlarged fragmentary plan parts being broken away for clearness of the disclosure.

Fig. 5 is a fragmentary section similar to that of Fig. 3, but showing the parts differently positioned.

Fig. 6 is a fragmentary side elevation of the machine showing the entrance slot for the auxiliary record card.

Fig. 7 is a longitudinal vertical central section showing the mounting at the rear end of the platen and the position of the stop plate relative thereto.

Referring more particularly to the drawings for a complete detailed description of the embodiment of the invention there shown, the present improvements are disclosed as being applied to an autographic register having known features of construction and embodying a casing 10 provided with an interior storage compartment at one end for the reception of a supply of record strips R assembled in superposed relation in the form of a zigzag folded supply pad or pack R', the strips being led from the pad over suitable guiding mechanism to the platen or writing table 11 upon which they are supported for manifolding inscription. The machine shown is provided at its forward part with a storage compartment 12 in which one or more of the record strips may be folded by appropriate folding mechanism and retained intact from unauthorized access. Forwardly of the platen and intermediate the supply the storage compartments is a feeding and folding mechanism for the record strips which as shown, may include a main feed shaft 13 carrying for rotation therewith feed

disks 14 adapted to grip the record strips against an overlying feed roll 15 carried by a housing and support 16 mounted for swinging movement to and from operative position upon pivoted supporting arms 17, and retained in operative position by means of appropriate latching mechanism 17^a. An operating handle 18 is attached to the external end of the operating shaft 13 and a spring 10 pressed retractable stop 19 is mounted upon the casing wall in position to contact with the operating handle to limit rotation of the operating shaft to a single revolution, until the stop is manually retracted to release the handle to further rotation. The feed disks are thus limited to a feeding cycle of a single revolution, this being sufficient to advance the record strips the length of a printed form and to align said strips by entry of the feed disk edges in feed controlling and aligning apertures formed in the strips in a manner well known in the art.

A cover 20 adapted to overlie the writing platen and having an inscription opening 25 aligning with said platen is pivoted at one side of the machine to suitable supporting brackets 21. This cover carries at its free or swinging edge a clamp 22 pivoted thereto for clamping the forward ends of the carbon or similar transfer sheets C in interleaved or transfer relation with the record strips above the platen.

For supporting the carbon sheet supply roll C' in position on the machine a supporting housing 23 is mounted at the side of the machine opposite to clamp 22, being preferably pivotally mounted as shown at 24 by means of supporting lugs or ears 25 pivoted to the brackets 21. The cover plate 20 and carbon housing may thus swing independently of each other as clearly shown in Figs. 3 and 5, said housing being thus adapted to be disposed outwardly at the side of the machine as shown in Fig. 5, or upwardly as in Fig. 3, with its receiving opening 26 positioned against the upper face of the cover 20 thus forming a closure for the carbon housing and presenting a neat and finished appearance. The receiving opening 26 is preferably formed in the side of the housing 23 for convenient insertion and removal of the supply roll C' and a swinging retaining plate 27 is pivotally carried within the housing by a rod 28 mounted in the end plates 55 thereof and having an external operating handle 29 and a spring 30 tensioned to hold the retaining plate in contact with the roll C' to retain the latter in position within the housing. The opening 26 is also conveniently positioned so as to permit easy threading of the carbon strips through a longitudinally extending slot 20^a in the cover plate into manifolding position over the platen, as will be clear upon reference to Figs. 65 3 and 5.

Overlying the platen 11 and spaced slightly thereabove is a shield or stop plate 31 forming with the platen a slot or pocket 32 for the reception of an auxiliary record card A, such for example as a card for use in tabulating machines and having thereon a blank form for the reception of certain data or information desired for tabulations. The stop plate may be supported in its operative position in superposed relation with the platen as shown in the drawing by means of supporting and spacing ribs 33, and may be folded around the rear edge of the platen or otherwise appropriately attached to the platen at shown in Figure 7, to provide a smooth guiding surface for the record strips R in their passage into writing position upon the platen. The stop plate is so shaped or so provided with cut away portions as to expose certain areas of the auxiliary card to inscription reception while shielding or stopping off other areas thereof on which inscription is not desired, as will be clear upon reference to Fig. 4 showing an auxiliary card in inscription receiving position within the pocket 32, said card being accurately positioned by stops which may be provided for example by the spacing ribs 33. The stop plate may be secured in position by screws or other securing devices. Guide plates 34 may be attached to the inside of the cover plate 20, positioned to rest (when the cover is down) upon the top surface of the stop plate 31, and in guiding relation with the lateral edges of the record strips R for retaining the latter in correct writing position. Due to the fact that the stop plate 31 supports the record strips R in inscription-receiving position, it may be regarded as an upper or auxiliary platen plate.

As clearly shown in Figs. 3 and 5 the stop plate 31 extends laterally at one edge beyond the plane of the side wall of the casing 10 and positioned immediately below this projecting edge is a bracket or plate 35 secured to the casing 10 and having a downwardly curved smooth guiding surface opposing the stop plate 31 and having a centrally disposed finger opening 36 therein. Positioned adjacent the outer edge of the stop plate 31 are guide members or blocks 36^a having curved surfaces opposing the surface of the guide plate or bracket 35. By means of this construction and arrangement an entrance slot or passageway is provided for the card A, communicating at its inner end with the pocket 32 whereby the card may be readily inserted into manifolding position with the strips R and carbon sheets C over the platen. The auxiliary card or sheet is guided at its edges into the entrance slot 32 by means of a laterally disposed guiding plate 37 at one edge and at the other edge by means of one of the hinge brackets 21. By virtue of the construction above set 125

forth it will be observed that an auxiliary record card or sheet A may be readily inserted at any time through the entrance slot into the receiving pocket 32 into manifolding position, and when so positioned certain portions of the face of the card will be exposed to reception of an inscription made upon the top record strip R, it being understood that the lower carbon sheet C has its lower carbonized face in position for contact with the upper face of the auxiliary card as clearly appears in Fig. 4. After this selective inscription has been entered the auxiliary card may be removed independently of movement of the record strips.

When the auxiliary card is thus inserted or removed it will be understood that the housing 33 will be moved upwardly as shown in Fig. 3 so as to leave the entrance slot entirely unobstructed permitting free insertion and removal of the card. When it is desired to lift the cover 20, as for example when the carbon strips are inserted or adjusted, the carbon housing 23 may be swung outwardly over the entrance slot and in this position as suggested in Fig. 5, the ends of the carbon sheets may be led forwardly and threaded through the cover slot 20^a into position for placing in interleaved relation with the record strips R. The cover is then swung into normal position and the carbon housing moved to resume the position as shown in Fig. 3.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language might be said to fall therebetween.

Having described our invention what we claim as new and desire to secure by Letters Patent is:

1. In a manifolding device, in combination, means for feeding a traveller record strip and supporting it in position for reception of an inscription, supporting means for supporting transfer material with parts thereof in transfer relation with the record strip, a support for supporting an auxiliary record card for independent insertion into manifolding relation with said traveller record strip and transfer material and for independent removal from manifolding position, and a passageway opening laterally at the outside of one side of the manifolding device for

insertion or removal of said card to and from manifolding position on said support.

2. In a manifolding device, in combination, means for feeding a traveller record strip and supporting it in position for reception of an inscription, supporting means for supporting transfer material in transfer relation with the part of the record strip in inscription receiving position, a support for supporting an auxiliary record card with a part of the inscription area thereof in cooperative inscription receiving relation with said record strip and said transfer material, and shielding means for effecting selective inscription reception upon parts of said auxiliary record card in superposed relation with said record strip.

3. In a manifolding device, in combination, means for feeding a traveller record strip and supporting it in position for reception of an inscription, supporting means for supporting transfer material with parts thereof in transfer relation with the record strip, a support for supporting an auxiliary record card for independent insertion into manifolding relation with said traveller record strip and transfer material and for independent removal from manifolding position, and means for shielding from inscription reception a part only of said auxiliary record card when inserted in superposed relation with said record strip.

4. In a manifolding device, in combination, means for feeding a traveller record strip and supporting it in position for reception of an inscription, supporting means for supporting transfer material in transfer relation with the part of the record strip supported in inscription receiving position, a support for supporting an auxiliary record card in manifolding relation with said traveller record strip, and a stop plate for overlapping said record strip for effecting selective inscription reception by said auxiliary record card when inserted in superposed manifolding relation with said record strip.

5. In a manifolding device, in combination, means for feeding a traveller record strip and supporting it in position for reception of an inscription, supporting means for supporting transfer material with parts thereof in transfer relation with the record strip, a support with a receiving passageway leading thereto, said support positioned for supporting an auxiliary record card for independent insertion through said passageway into manifolding relation with said traveller record strip and transfer material and for independent removal from manifolding position, a swingably mounted cover adapted to be swung into overlying position with said record strip, and a transfer sheet supply housing swingably mounted adjacent to said cover.

6. In a manifolding device, in combina-

- tion, means for feeding a traveller record strip and supporting it in position for reception of an inscription, supporting means for supporting transfer material with parts thereof in transfer relation with the record strip, a support for supporting an auxiliary record card for independent insertion into manifolding relation with said traveller record strip and transfer material and for independent removal from manifolding position, an entrance slot for said auxiliary card positioned laterally alongside of the said inscription receiving position, and a transfer strip supply housing movably mounted for movement into obstructing and non-obstructing positions with said entrance slot.
7. In a manifolding device, in combination, means for feeding a traveller record strip and supporting it in position for reception of an inscription, supporting means for supporting transfer material with parts thereof in transfer relation with the record strip, a support for supporting an auxiliary record card for independent insertion into manifolding relation with said traveller record strip and transfer material and for independent removal from manifolding position, an entrance and removal slot for said auxiliary card positioned laterally along side of the said inscription receiving position, a transfer strip supply housing movably mounted for movement into obstructing and non-obstructing positions with said entrance slot, and a swingably mounted cover adapted to be swung into overlying position with said record strip and being mounted adjacent to said supporting housing.
8. In a manifolding device, in combination, means for feeding a traveller record strip and supporting it in position for reception of an inscription, supporting means for supporting transfer material with parts thereof in transfer relation with said record strip, a support for supporting an auxiliary record card for independent insertion into manifolding relation with said traveller record strip and transfer material and for independent removal from manifolding position, an entrance and removal slot for said auxiliary card positioned laterally along side of the said inscription receiving position, a transfer strip supply housing movably mounted for movement into obstructing and non-obstructing positions with said entrance slot, and a swingably mounted cover adapted to be swung into overlying position with said record strip and being mounted adjacent to said supply housing, said cover having a slot through which the transfer sheet may be passed into manifolding position and said housing having a receiving opening and being movable into position against said cover so as to close said opening.
9. In a manifolding device, in combination, a platen, means for feeding a traveller rec-

ord strip into manifolding position upon said platen, and a stop plate overlying said platen and forming therewith a pocket for the reception and support of an auxiliary record card in manifolding relation with the record strip upon said platen and having parts omitted over the platen to expose the auxiliary card to reception of an inscription while stopping off other parts thereof from inscription reception.

10. In a manifolding machine, in combination, a platen, means for feeding the traveller record strip to position successive recording areas thereof in inscription receiving position upon said platen, a stop plate in superposed relation with said platen and forming a pocket for reception of an auxiliary record card so as to expose parts of said card to inscription reception and to stop off other parts thereof, said pocket having an entrance slot positioned laterally adjacent to the platen, and a movable transfer sheet housing positioned adjacent said entrance slot and being movable into obstructing and non-obstructing positions with said slot.

11. In a manifolding machine, in combination, a platen, means for feeding a traveller record strip to position successive recording areas thereof in inscription receiving position upon said platen, a stop plate in superposed relation with said platen and forming therewith a pocket for reception of an auxiliary record card so as to expose parts of said card to inscription reception and to stop off other parts thereof, said pocket having an entrance slot positioned laterally adjacent to the platen, a movable transfer sheet housing positioned adjacent said entrance slot and being movable into obstructing and non-obstructing positions with said slot and having a receiving opening in the side thereof, a cover plate or shield swingably mounted adjacent said transfer sheet housing and having a slot through which the transfer sheet passes to the platen, said housing being adapted to move against said cover plate to close its receiving opening.

12. In a manifolding machine, in combination, a platen, means for feeding a traveller record strip to position successive recording areas thereof in inscription receiving position on the platen, and a transfer sheet supply housing pivoted adjacent the platen and having a receiving opening in the side thereof in position to be closed by movement of the housing against the machine.

13. In a manifolding machine, in combination, a platen, means for feeding a traveller record strip to position successive recording areas thereof in inscription receiving position on the platen, a cover plate swingably mounted at one side of the machine, and a transfer sheet supply housing movably mounted adjacent to the mounting of said cover plate and having an opening in the

side thereof in position to be closed by movement of said housing against the top face of said cover plate.

14. In a manifolding machine, in combination, a platen for supporting a record strip in inscription receiving position, a pocket adjacent said platen for reception of an auxiliary record card, an entrance slot for said pocket at the side of the machine, and a transfer sheet supply housing pivotally mounted adjacent to said slot and being movable to obstructing and non-obstructing positions with reference thereto.

15. In a manifolding machine, in combination, a support for supporting a traveller record strip in inscription-receiving position, a support for supporting transfer material in transfer relation with the record strip, a card support for supporting an auxiliary record card in manifolding relation with said record strip and said transfer material, and a passageway opening laterally of record strip feed and leading to said card support so as to permit lateral insertion of the auxiliary card into manifolding relation.

16. In a manifolding device, in combination, upper and lower platen plates spaced apart in different levels over which a traveller record strip may be fed, a supporting pocket for receiving and supporting an auxiliary record sheet with parts thereof overlying the lower platen plate and parts underlying the upper platen plate so as to effect selective inscription thereon, and a receiving passageway for said pocket opening laterally of the direction of record strip feed.

17. In a manifolding device, in combination, a cover plate mounted for swinging movement at one side of the manifolding device, and a transfer sheet supply housing pivotally mounted on the same side of the device with said cover plate.

18. In a manifolding device, in combination, a cover plate pivotally mounted for swinging movement at one side of the manifolding device, and a transfer sheet supply housing pivotally mounted on the same side of the device with said cover plate, said supply housing and said cover plate being positioned for swinging movement on their pivotal mountings in the same path.

In testimony whereof we affix our signatures.

WILLIAM A. PRINGLE.
LOUIS FRED HAGEMANN.
